WILLIAM A. SMITH, OF EASTON, PENNSYLVANIA, ASSIGNOR TO INGERSOLL-RAND COMPANY, OF JERSEY CITY, NEW JERSEY, A CORPORATION OF NEW JERSEY.

VALVE FOR PERCUSSIVE TOOLS.

1,343,649.

Specification of Letters Patent. Patented June 15, 1920.

Application filed December 11, 1918. Serial No. 266,286.

To all whom it may concern:

Be it known that I, WILLIAM A. SMITH, a citizen of the United States, residing at Easton, in the county of Northampton and State of Pennsylvania, have invented a certain new and useful Improvement in Valves for Percussive Tools, of which the following is a specification.

This invention relates to a percussive tool primarily adapted for drilling rock but which may be utilized for any other purpose where a percussive element is rapidly reciprocated and struck against the end of a drill steel or other tool. The tool has a cylinder in which reciprocates a piston or hammer which is usually detached from the drill steel but which may be attached to the drill steel as in a piston drill.

The objects of the present invention are to provide a percussive tool, drill sharpener, or rock drill of the above type, commonly referred to as hammer tools, with a symmetrical differential piston; that is, one having two pressure areas to force the piston forwardly, and one to return the piston, which may be reversed end for end so that when one end becomes worn or broken due to striking the end of the drill steel it may be reversed end for end and a new face presented to strike the drill steel at the forward end of its stroke.

Also, a further object of the invention is to provide a valve for tools of the above description which will control the admission of motive fluid to one end of the cylinder and control the exhaust of the fluid through auxiliary exhaust ports from both ends of the cylinder, pressure fluid being admitted to the opposite ends of the cylinder through a piston controlled port and the cylinder being further supplied with a continuously open exhaust port located approximately centrally of the cylinder.

A further object of the present invention is to provide a valve forced in one direction by pressure constantly exerted against one end and thrown in the opposite direction by a fluctuating pressure against its opposite end, the valve, furthermore, being made quickly responsive to the movements of the piston by means of bleeder or leak ports provided within the valve.

With the above and other objects in view, my invention consists of the features of construction and operation described in the fol-

lowing specification and shown in the accompanying drawings, in which:

Figure 1 shows an enlarged view in section of the valve especially adapted for use in the hammer type of percussive tool, the view being taken longitudinally of the valve;

Fig. 2, a longitudinal view of the complete tool, in section, showing the piston near the rear end of its stroke, and

Fig. 3, a view similar to Fig. 2, showing the location of the piston and valve at the forward extremity of the piston stroke, in which position it strikes the drill steel.

Referring more particularly to the figures of the drawing, in which like references refer to like parts, 1 shows the cylinder, which, as shown in the drawings, is made in one piece, but obviously, if desired, may be made up of several separate parts. Within the cylinder 1 reciprocates the piston or hammer, shown generally at 2, having a centrally disposed head 3 and two extensions 4-4 extending from either face of said head 3 which are similar to each other, both in length and in diameter. The forward end of the cylinder 1 is closed by a suitable front head 5 of any desired type, the one shown in the figures being purely diagrammatic. The cylinder 1 is provided with a valve chest 6 which may be integral with the cylinder 1 or made up as a separate part, in which reciprocates a cylindrical valve 7 within a suitably bored chamber 8 of the valve chest 6. Between the cylinder 1 and valve chamber 8 are a plurality of ports 9, 10, 11, 12 and 13, each having a function presently to be described, and from the valve chamber 8 to atmosphere extends a large port 14 which is open to the atmosphere in any position of the valve 7.

Motive fluid is supplied to the drill through a suitable inlet 15 having a port 16 admitting motive fluid to the rear end of the cylinder 1 within the chamber 17 and exerting a constant pressure against the rear end of the piston extension 4. From the chamber 17 extends a passage 18 which is in communication with an extension of the valve chamber 8 indicated at 19 and between the opening or chamber extension 19 and the rear end of the cylinder within which the head 3 of the piston operates, is the port 13 above referred to. From the position of the piston indicated in Fig. 2 it will be seen that fluid pressure may pass in the di-

rection of the arrows into the rear end of the piston chamber behind the main head 3 thus forcing the piston or hammer 2 forwardly, the fluid pressure in advance of the 5 piston being exhausted through the ports 10 and 11 through the valve chamber 8 and out to the atmosphere through the port 14. As soon as the piston 2 reaches the position indicated in Fig. 3 the rear extension 4 of 10 the piston 2 passes a port 20 communicating with a passage 21 which directs motive fluid into the front end of the piston chamber, thus reversing the movement of the piston 2, and, at the same time, the valve 15 head 25 is moved to clear port 9 by the pressure built up through leak port 24 and the valve is then thrown into the position indicated in Fig. 3 by the pressure built up in the forward end of the cylinder. This 20 action of the valve takes place against the constant pressure exerted in the extension 19 of the valve chamber, by reason of the fact that the valve chamber 8 preferably has at least twice the area of the chamber 25 extension 19. During the reverse stroke of the piston, that is, while it is moving to the rear end of the cylinder, the exhaust port 12 is open during the major portion of the stroke and as soon as the piston head 3 30 passes the port 11 pressure immediately drops in the forward portion of the piston chamber and also in the front end of the valve chamber 8, thus allowing the valve 7 to be thrown again to the position shown in Fig. 2. In order to accomplish the reversal of movement of the valve 7 quickly and at the critical points in the stroke of the piston 2 a passage is bored longitudinally of the valve 7 as shown at 22 which 35 40 is continued by a smaller passage 23 in communication therewith. Forwardly of the passage 23 is a small leak port 24 opening into the front end of the valve chamber 8 past the forward head 25 of the valve. Not 45 only does this passage through the valve formed by passages 22, 23 and leak port 24 serve to make the valve more lively and quicker in its action but also serves to supply fluid to the air cushion pockets formed 50 at either end of the valve chamber 8 and shown at 30 and 31. Within either of these 55 pockets 30 and 31 motive fluid is trapped so that the valve 7 can not come in contact directly with the end walls of the valve chamber 8.

A second head is provided on the valve 7 as shown at 26, and extending a short distance from the rear end of the head 26 the valve 7 is provided with an extension 27 60 having approximately one half the cross sectional area of the heads 25 and 26. Just rearwardly of the head 26 extends a short leak port 28 opening into the rear end of the valve chamber 8. As pressure is 65 constantly exerted against the rear extension

27 of the valve 7 fluid passes continuously into the passage 22 and passage 23 and from these passages to the forward end of the valve and also to the space between the head 26 and the rear end of the valve chamber 8 70 so that pressure is constantly being supplied to both ends of the valve chamber 8 and as soon as there is a pressure drop in the piston chamber there is a corresponding drop at the forward end of the valve chamber 75 and the valve is immediately thrown to forward position. A port 29 leads from a point located a short distance from the rear end of the piston chamber 8 to atmosphere, thus providing a short cushion chamber 30 to cushion the action of the valve at the rear end of its stroke and to which the leak port 28 tends to supply sufficient motive fluid to aid in the reversal of the movement of the valve, as well as aid in cushioning the valve. The port 11 is constantly open to atmosphere as it is not overrun by either of the heads 25, 26 of the valve 7 and this port has the usual functions of the central cylinder exhaust port usually found in 80 drills of this type; that is, to exhaust a large part of the motive fluid at the end of each stroke. Port 10, which is forward of port 11, serves as an anti-compression port for the forward end of the piston cylinder 95 and is open during the forward stroke of the piston. The port 12, which acts as an anti-compression port or auxiliary exhaust for the rear end of the cylinder, is open during the return stroke of the piston, until 100 overrun by the piston 2, but during the forward stroke is overrun and thus closed by the head 26 of the valve 7.

From the above the construction and operation of the tool will be clearly understood, and it is to be understood that while the present showing and description disclose only one specific embodiment of my present invention, other forms and modifications are included within the spirit and scope of the invention as expressed in the appended claims.

What I claim is:

1. In a fluid operated reciprocating motor adapted for a percussive tool of the hammer type, the combination of a cylinder, a piston therein and a valve to control the reciprocations of said piston, said valve being forced continuously in one direction by constant pressure against one end and thrown in the opposite direction by a fluctuating pressure against its opposite end, said opposite end being larger than said first mentioned end, and having a leak port whereby fluid may be supplied through said valve to aid in the reversal of movement of the valve.

2. In a fluid operated reciprocating motor adapted for a percussive tool of the hammer type, the combination of a cylinder, a piston

therein and a valve for controlling the reciprocations of said piston, said valve being forced continuously in one direction by constant pressure against one end and thrown 5 in the opposite direction by a fluctuating pressure against its opposite end, said opposite end being larger than said first mentioned end, said valve controlling auxiliary exhaust ports from both ends of the cylinder and thrown to its forward position upon 10 reduction of pressure in the forward end of the cylinder as the piston overruns an independent central exhaust port.

3. In a fluid operated reciprocating motor 15 adapted for a percussive tool of the hammer type, the combination of a cylinder, a piston therein and a valve to control the reciprocations of said piston, said valve being forced continuously in one direction by constant pressure against one end and thrown 20 in the opposite direction by a fluctuating pressure against its opposite end, said opposite end being larger than said first mentioned end, and having a leak port whereby 25 fluid may be supplied through said valve to aid in the reversal of movement of the valve, said valve controlling auxiliary exhaust ports from both ends of the cylinder and thrown to its forward position upon reduction 30 of pressure in the forward end of the cylinder as the piston overruns an independent central exhaust port.

4. In a fluid operated reciprocating motor 35 adapted for a percussive tool of the hammer type, the combination of a cylinder, a piston therein and a valve controlling the reciprocations of said piston, said valve being forced continuously in one direction by constant pressure against one end and thrown 40 in the opposite direction by a fluctuating pressure against its opposite end, said opposite end having a greater area than that of said first mentioned end and being provided with a leak port whereby fluid may be supplied 45 through said valve to aid in the reversal of movement of the valve.

5. In a fluid operated reciprocating motor 50 adapted for a percussive tool of the hammer type, the combination of a cylinder, a piston therein and a fluid actuated valve controlling the admission of fluid to one end of the cylinder and the exhaust of a part of the motive fluid from both ends of said cylinder, said valve having a head at one end, a 55 head near the other end and an extension extending from said second head against which fluid pressure is adapted to be constantly exerted, and means to supply a small additional amount of fluid to said head at 60 the end of the valve to aid in the reversal of movement of said valve.

6. In a fluid operated reciprocating motor 65 adapted for a percussive tool of the hammer type, the combination of a cylinder, a piston

therein and a fluid actuated valve controlling the admission of fluid to one end of the cylinder and the exhaust of a part of the motive fluid from both ends of said cylinder, said valve having a head at one end, a head near the other end and an extension 70 extending from said second head against which fluid pressure is adapted to be constantly exerted, the area of said extension being less than the area of either of said heads and means to supply a small additional amount of fluid to said head at the 75 end of the valve to aid in the reversal of movement of said valve.

7. In a fluid operated reciprocating motor 80 adapted for a percussive tool of the hammer type, the combination of a cylinder, a piston therein and a valve controlling the reciprocations of said piston, said valve being provided with a passage throughout its length, and with a port extending from said passage to the outer surface of said valve, said passage and port being constantly open to fluid pressure and thereby permitting fluid to pass through said valve continuously and build up pressure in the valve chamber 85 when the valve is at either end of its stroke to aid in throwing the valve to its opposite position.

8. In a fluid operated reciprocating motor 90 adapted for a percussive tool of the hammer type, the combination of a cylinder, a piston therein and a valve controlling the reciprocations of said piston, said valve being provided with a passage throughout its length, and with a port extending from said passage to the outer surface of said valve near 95 one end, said passage and port being constantly open to fluid pressure and thereby permitting fluid to pass through said valve continuously and build up pressure in the valve chamber 100 when the valve is at either end of its stroke to aid in throwing the valve to its opposite position and to cushion the valve at the end of its stroke.

9. A reciprocating motor operated by 105 fluid pressure, comprising a cylinder having a piston therein, said piston having differential diameters and a rearward extension, a valve having differential diameters and a rearward extension, constant pressure being exerted against the rearward extensions of said valve and piston, said valve being controlled by the exhaust from the front end of the cylinder, and thrown to its forward position as pressure is exhausted from 115 the front end of the cylinder and thrown to its rearward position as pressure is admitted to the forward end of the cylinder.

In testimony whereof I have hereunto set my hand.

WILLIAM A. SMITH.
